PHASE STABILIZATION OF R. F. AMPLIFIERS
AND OSCILLATOR CIRCUITS

Richard J. Bousek, Cedar Rapids, Iowa, assignor to Collins Radio Company, Cedar Rapids, Iowa, a corporation of Iowa

Application July 23, 1953, Serial No. 369,930

2 Claims. (Cl. 250—36)

This invention relates in general to means for stabilizing the phase of electronic circuits and in particular to stabilizing and controlling the phase of amplifier and oscillator circuits.

In conventional amplifier or oscillator circuits employing inductive-capacitive-resistance resonant circuits in either the grid, plate or cathode, at a given point in the circuit the relative phase angle with respect to the driving point (amplifier) or any other selected point in the circuit (oscillator), varies when the signal is slightly off the LCR resonant frequency.

It is oftentimes desirable to maintain a fixed phase relationship and the normal phase shift is therefore undesirable.

It is an object of this invention therefore to provide a phase stabilizing circuit wherein frequency deviations from resonance do not cause an undesirable phase shift.

Another object of this invention is the provision for a reflective impedance which compensates for the standard phase shifts at frequencies off resonant.

A feature of this invention is found in the provision for the addition of a dummy tuned circuit which is inductively coupled to an electronic circuit so as to obtain increased stability.

Further objects, features and advantages of this invention will become apparent from the following description and claims when read in view of the drawings, in which:

Figure 1 illustrates a conventional amplifier;

Figure 2 illustrates the standard phase angle relationship plotted against frequency, and also the voltage across the circuit plotted against frequency;

Figure 3 illustrates an oscillator circuit wherein crystals are switched;

Figure 4 illustrates an amplifier according to this invention;

Figure 5 illustrates a crystal oscillator circuit with the apparatus of this invention;

Figure 6 illustrates a double tuned circuit wherein the principles of this invention are utilized;

Figure 7 illustrates the phase and voltage relationships of the apparatus according to this invention plotted against frequency; and

Figure 8 illustrates curves for different parameters than in Figure 7.

Figure 1 illustrates a tube V_1 which has a control grid 10 connected to the output of a signal generator 11. The plate 12 of tube V_1 is connected to a tuned circuit designated generally as 13 and which comprises a condenser C_1 and inductance L_1 . The output is removed from the coupling condenser C_2 in conventional fashion.

Figure 2 illustrates the output voltage E_0 plotted against frequency and it is to be noted it has a normal peak at the resonant frequency f_0 . Also plotted on this curve is a curve of phase angle versus frequency which is at zero at f_0 and leads or lags at other frequencies.

Figure 3 illustrates a conventional fundamental over-tone frequency oscillator circuit wherein crystals 14 and 15 may be selectively switched in the input circuit. A

2

tube V_3 receives an input from the crystal and has an output RLC circuit 16 comprising a condenser C_3 , a resistor R_1 and an inductance L_3 . An amplifier tube V_2 has its cathode 17 connected to the crystal 14 to drive it. In such a circuit if the LCR circuit 16 is resonant at the crystal frequency, it appears resistive and produces no phase shift. However, as the resonant frequency of the circuit 16 is varied, a phase shift is introduced resulting in a change in frequency of oscillation. This is generally referred to as "pulling" the crystal.

The general phase relationship of the circuit shown in Figure 3 is similar to that shown in Figure 2.

Apparatus according to this invention is shown in Figure 4 wherein a tube V_4 receives an input on its control grid 17 from a signal generator 18 and has its plate 19 connected to an output E_0 through a coupling condenser C_4 . An RLC resonant circuit 21 comprising a condenser C_5 , inductance L_5 and resistance R_5 is connected between the plate 19 and a suitable B plus voltage.

Mutually coupled to the inductance L_5 is an inductance L_6 which is connected in series with a condenser C_6 and a resistor R_6 . A capacitive shield 22 which might be, for example, a copper plate that allows magnetic flux to pass therethrough, provides a Faraday shield. The shield is mounted between the RLC circuits 21 and 23 to prevent capacitive coupling from being reflected between them.

The circuits 21 and 23 are resonant at the same frequency and transformer theory shows that for inductive coupling there is reflected from a secondary to primary a purely resistive component. (See Terman's Radio Engineering Handbook, section 3.)

Experiments and tests carried on by the applicant have shown that for small variations in frequency the reactive component reflected from the secondary L_6 to the primary L_5 has a sign opposite to that of the primary reactance and may be made to equal, to exceed or to be smaller in magnitude than the primary reactance by adjusting the parameters Q , the coupling, and/or the LC ratio.

Variation of these factors allows the phase shift to be stabilized and controlled over a range of frequencies above and below the resonant frequency of the circuits.

Figure 5 illustrates a crystal controlled oscillator wherein in a tube V_5 which is an amplifier is connected to a bank of crystals 25 and 26 that supply an input to the cathode 27 of a tube V_6 . A resonant circuit 28 comprising a condenser C_7 , inductance L_7 and resistor R_7 is connected in the plate circuit of tube V_6 . A Faraday shield 29 is mounted between the inductance L_7 and a second inductance L_8 which is connected in series with a condenser C_8 and a resistor R_8 . Inductors L_7 and L_8 may be varied by shaft 31 which moves them as crystals are switched.

Variation of the LC ratio, closeness of coupling, and Q in the circuits 28 and 30 allows the phase angle to be controlled.

The circuit of Figure 6 is similar to that shown in Figure 4 except it has a tuned input and a tuned output. A signal generator 32 is coupled to a tuned input circuit 33 which comprises an inductor L_9 , a resistor R_9 and a condenser C_9 . A Faraday shield 34 is mounted between the inductor L_9 and an inductor L_{10} which is in series with condenser C_{10} and resistor R_{10} .

The tube V_7 has its control grid 36 connected to the circuit 33 and has its plate 37 connected to an output RLC circuit 38 comprising a condenser C_{11} , inductor L_{11} and resistor R_{11} . A Faraday shield 39 is mounted between the inductor L_{11} and an inductor L_{12} which is in series with a resistor R_{12} and the condenser C_{12} .

Figure 7 illustrates how the phase angle may be controlled as the frequency varies from resonance for a circuit such as shown in Figure 4. The phase angle curve is designated by the numeral 41 and the amplitude curve is designated by the numeral 42. These particular curves

were plotted with a Q of 62.8 and a coupling coefficient of 0.7. It is to be noted that at the resonant frequency f_0 , the phase angle curve is flat which illustrates that for variations in the vicinity of f_0 , no phase shift occurs as does the circuit of Figure 1.

Figure 8 illustrates the response of the circuit in Figure 4 with different parameters than in Figure 7. Here the curve 43 represents phase angle versus frequency and the curve 44 represents voltage across the tuned circuit plotted against frequency. Q was 18.7 and the mutual coupling between L_5 and L_6 was 10.2 microhenries. It is seen that the phase angle may be held linear over a substantial range of frequencies.

The phase angle curve may be given a slope opposite to that shown in Figure 2 by varying the controlling parameters Q, coupling, and LC ratio.

It is seen that this invention allows the phase and voltage of circuits to be controlled by adding dummy tuned circuits.

Although this invention has been described with respect to particular embodiments thereof, it is not to be so limited as changes and modifications may be made therein which are within the full intended scope of the invention, as defined by the appended claims.

I claim:

1. An oscillator circuit wherein phase shift may be controlled comprising, an electron tube, a frequency stabilizing element connected to one of the electrodes of said electron tube, a first resonant circuit comprising an inductor and capacitor connected in the output circuit of said electron tube, a dummy resonant circuit comprising a second inductor and a second capacitor having a resonant frequency the same as said first resonant circuit, the second inductor mutually coupled to the first inductor, said cou-

pling being variable thereby varying the reflective impedance, and a capacitive shield mounted between the first resonant circuit and the dummy resonant circuit for shielding them capacitively while not interfering with the magnetic coupling.

2. An oscillator circuit wherein phase shift may be controlled comprising, an electron tube, a frequency stabilizing element connected to one of the electrodes of said electron tube, a first resonant circuit comprising an inductor, a capacitor and a resistor connected in the output circuit of said electron tube, a dummy resonant circuit comprising a second inductor, a second capacitor and a second resistor, the second inductor mutually coupled to the first inductor, said coupling being variable thereby varying the reflective impedance, and a capacitive shield mounted between the first resonant circuit and the dummy resonant circuit for shielding them capacitively while not interfering with the magnetic coupling.
